UNITED STATES PATENT OFFICE.

WORTHIE W. MOREY, OF COLUMBUS, OHIO.

VENTILATOR.

1,348,513.

Specification of Letters Patent. Patented Aug. 3, 1920.

Application filed August 25, 1919. Serial No. 319,545.

To all whom it may concern:

Be it known that I, WORTHIE W. MOREY, a citizen of the United States, residing at Columbus, in the county of Franklin and 5 State of Ohio, have invented certain new and useful Improvements in Ventilators, of which the following is a specification.

This invention relates to ventilators and it has for its object the provision of an 10 proved device of this character constructed in such manner as to effectually inject fresh air into a space to be ventilated or to eject foul air therefrom.

It is one of the objects of the invention to 15 provide a ventilator of the character indicated that will be extremely sensitive in action, operable by very light currents of air and capable of rendering efficient service upon buildings that are surrounded by 20 higher buildings.

It is a further object of the invention to 25 provide a ventilator constructed in such manner that the passage of the wind laterally thereby will aid in drawing foul air from the structure to which the ventilator 30 is applied.

It is a further object of the invention to 35 provide a ventilator adapted for use in connection with cars or other moving vehicles, boats and the like.

It is another object of the invention to 40 provide a ventilator constructed in such manner that it will be thoroughly weather proof.

Further objects and advantages of the 45 invention will be set forth in the detailed description which now follows:

In the accompanying drawings:

Figure 1 is a vertical, sectional view of a 50 ventilator constructed in accordance with the invention;

Fig. 2 is a horizontal, sectional view through the propelling hemispheres herein-after described; and

Fig. 3 is a horizontal, sectional view 55 through a centrifugal fan herein-after described.

Like numerals designate corresponding parts in all of the figures of the drawing.

Referring to the drawing 5 designates a 60 tubular stem adapted to be connected to a structure to be ventilated, whether the latter be a building, a car, a vessel or otherwise. A frame secured to the stem 5 comprises the vertical portions 6 that rest 65 against and are directly connected to the

stem, outwardly extending portions 7 and a yoke-like portion 8 which spans the remainder of the structure hereinafter described. The stem 5 is spanned by a spider 9. A 60 threaded stem 10 of a lower bearing holder 11 is screwed into the spider 9. This bearing holder carries a glass bearing 12 which receives the lower end of a spindle 13 by which all of the rotative parts of the structure are carried. The lower end of the spindle is pointed at 14 to adapt it to engage within a correspondingly shaped recess 15 of the glass bearing. The bearing 12 is held 65 in position by screws 16, the inner ends of which overlap the bearing. It is manifest that by rotating the bearing holder 11 a vertical adjustment may be imparted to said bearing holder and consequently to the bearing. The upper end of the spindle 13 carries a spherical enlargement 17 that operates in an elongated recess 18 of an upper glass bearing 19. The bearing 19 is mounted in an upper bearing holder 20 that is provided with a threaded stem 21 that is 70 screwed into the top of the yoke 8 and carries a lock nut 22, by means of which the upper bearing holder may be bound in adjusted position. Screws 23 hold the upper glass bearing 19 in position in the holder 20. 75

The spindle 13 carries a hemisphere hub 24 that is secured to the spindle by a set screw 25. Brackets 26 carry hollow hemispheres 27 which serve as the propelling means for the stem 13, said hemispheres being secured to the brackets by rivets or like fastening devices 28. The brackets 26 are provided with threaded shanks 29 that are screwed into the hemisphere hub 24 and it is manifest that by screwing the shanks into 80 the hub to a greater or less degree an accurate balancing of the hemispheres upon the spindle 13 may be effected. Furthermore, this construction provides means for adjusting the angle of the hemispheres. If the 85 ventilator is being used upon a building that is surrounded by higher buildings these hemispheres may be adjusted to an upward angle so that they will be engaged and operated by downwardly directed deflected currents of air from the surrounding buildings. Set screws 30 carried by the hub 24 serve to bind the shanks 29 against movement, after the hemispheres have been adjusted to the desired position. If desired, small openings 100 27^a may be formed in the hemispheres to prevent them from retaining rain-water 105 110

when adjusted to an upward inclination as above set forth.

The spindle 13 carries a centrifugal fan 31, which consists of a cylinder having an open bottom and a closed top 32. The top carries a collar 33 which in turn is secured to the stem 13 by a set screw 34. Blades 35 are struck from the wall of the cylinder and, when the cylinder is rotated serve to discharge air from the interior of the cylinder outwardly. The centrifugal fan is disposed within a hemispherical weather-hood 36 that is open at the bottom and is secured to the frame or yoke 8 by screws or like fastening devices 37. A wind flange 38 encircles the upper end of stem 5 and, at, substantially, an angle of forty-five degrees. The function of this wind flange is to prevent wind from blowing upwardly into the weather-hood 36. An axially acting fan 39 is mounted upon the spindle 13 below the centrifugal fan and preferably within the neck 5.

The operation of the device is as follows:

Assuming that the ventilator is to be used 25 to eject foul air from the space to be ventilated the hemispheres 27 will be suitably set to impart the desired direction of rotation to the spindle 13. This will in turn impart rotation to the centrifugal fan and to the 30 axially acting fan 39. The fan 39 will act to draw the foul air through the stem 5 and discharge the same into the interior of the centrifugal fan and the centrifugal fan will act to discharge this foul air laterally into 35 the weather-hood 36, the shape of the interior of which is such as to deflect said air downwardly through the open bottom of said weather-hood as indicated by the arrows a.

If it be desired to employ the ventilator to discharge fresh air into a space to be ventilated the hemispheres 27 will be set to cause the spindle 13 to rotate in the proper direction and the centrifugal fan may be removed from the stem 13. The fan 39 will then act to discharge air downwardly through the stem 5. To render the weather-hood entirely weather tight, a weather flange 40 is mounted upon the top of the weather-hood and a weather cap 41 is mounted upon the spindle 13 and extends downwardly over the flange. This construction permits the free rotation of the spindle while maintaining the weather-hood proof against the entry 50 of rain or snow.

By having the weather-hood extend below the top of the stem 5, this stem is not only rendered effectually weather and storm proof but it provides a structure of such nature that when the winds blow across the mouth or under side of the weather-hood a vacuum or suction is created in the tubular stem 5, which aids in ejecting foul air from the building. The provision of the glass 60 bearings provides a structure wherein the 65

spindle may rotate without lubrication and substantially without friction. The spherical enlargement upon the upper end of the spindle reduces friction to a minimum when the same engages the perpendicular inside 70 surface of the bearing when revolving.

While I have shown a fan 39 upon the spindle 13 it is manifest that the action of the centrifugal fan alone would serve to draw air through the tubular stem 5 since, 75 when this fan throws the air contained therein outwardly into the weather-hood it tends to create a vacuum in the interior of the centrifugal fan into which air would flow through the tubular stem 5.

While I have referred to the drawing of foul air through the stem it is to be understood that this term includes hot air, fumes, gas, smoke, dust or any other fluid that it may be desired to discharge from the space 85 to be ventilated.

While the elements shown and described are well adapted to serve the purposes for which they are intended it is to be understood that the invention is not limited to the precise construction set forth but that it includes within its purview whatever changes fairly come within either the terms or the spirit of the appended claims.

Having described my invention, what I 95 claim is:

1. A device of the character described comprising a hollow stem, a hemispherical weather-hood having its open side disposed downwardly and located above said stem, 100 a centrifugal fan disposed within said hood and a wind operated propeller for actuating said fan.

2. A device of the character described comprising a hollow stem, a rotative spindle, 105 a fan upon the spindle and within the stem, said fan acting axially, a centrifugal fan upon the spindle above the first named fan, a weather-hood of inverted bowl shape within which the centrifugal fan is located and a propeller consisting of a plurality of hollow hemispheres disposed upon the spindle above the weather-hood.

3. In a device of the character described, the combination with a hollow stem, of a 115 spider spanning the same, a bearing holder vertically adjustable upon the spider, a glass bearing carried by the bearing holder, a stem having its lower end pointed for engagement with said bearing, a yoke carried by the 120 stem, an upper bearing holder vertically adjustable with respect to the yoke, a glass bearing carried by the upper bearing holder, the upper end of the spindle having a spherical enlargement which engages with a corresponding recess in the upper glass bearing, an axially acting fan upon the spindle within the stem, a centrifugally operating fan upon the spindle above the first named fan, 125 a hemispherical weather-hood having its 130

open side disposed downwardly which incloses the centrifugal fan, a co-acting weather flange and weather-cap upon the weather-hood and spindle respectively to prevent the entry of wind, rain, etc., and a propeller upon the spindle above the weather-hood.

4. A ventilator comprising a tubular stem, a weather-hood of inverted bowl shape of considerably greater diameter than the stem, concentrically overlying said stem with its lower edge disposed below the level of the upper end of the stem, a centrifugal fan of inverted cup shape overlying the mouth 15 of the stem within the hood and being of greater diameter than the stem so that the air from the stem may pass into the interior of said fan, said fan having tangential blades in its sides by which the air is positively ejected therefrom outwardly into the interior of the bowl shaped weather-hood, the latter acting to deflect said air downwardly and out of the space between the stem and the lower edge of the weather-

hood, a spindle by which the centrifugal fan 25 is carried and a propeller rotating said spindle.

5. A ventilator comprising a stem, a weather-hood of inverted bowl shape and of considerably greater diameter than the 30 stem, overlying said stem and having its lower edge disposed below the level of the top of the stem, a centrifugal fan of inverted cup shape disposed above the mouth of the stem the hollow interior thereof receiving the air from said stem, said fan comprising blades which eject the air from the interior thereof to the interior of the weather-hood, the curved walls of the latter deflecting said air downwardly and out of 40 the space between the stem and the lower part of the weather-hood, an axially acting fan within the stem, for directing air into the interior of the centrifugal fan, a spindle by which both of said fans are carried, and 45 a propeller upon said spindle.

In testimony whereof I affix my signature.
WORTHIE W. MOREY.
